FIG. 2

FIG. 3

FIG. 4

INVENTOR:
Paul Müller

UNITED STATES PATENT OFFICE

PAUL MÜLLER, OF SOLINGEN, GERMANY

SHAVING APPARATUS

Application filed November 10, 1928, Serial No. 318,580, and in Germany July 19, 1928.

The base of the cutting procedure is rapidity, but it is only due to the progress in technics in modern times that it has become possible to create this base and to manufacture the protecting comb of the safety razor of light metal and of the necessary thickness, placing the blade of the razor in such a safe manner that even with the quickest movement of shaving the cutting of the skin 5 is avoided. The well known safety razors are supplied with small ears which hold the blades at the exterior edges in a fixed position for use, or which are placed along the side of the blade between the projections. 10 In practical use it has been found that this construction is faulty as it is impossible to regulate the position of the blade, and also it is difficult to extract same from the protecting comb. As guides within the significance 15 of the present invention they are unsuitable, and all the more so since hollow ground blades, due to the manner of their preparation—forging and sharpening by hand—there is always a more or less important difference in mass work. The consequence is that owing to the lack of an exact 20 and precise lay-on surface, the blade when being inserted into the protecting comb or when being pressed against the skin, shifts slightly and no longer fulfills the required object. A very slight alteration of the position of the blade in the protecting comb suffices to destroy all protection of the cutting edge and thus produces severe wounds in the 25 skin when shaving. Moreover the ears at the side of the blade hinder the holding of same at the sides when taking it out or putting it into the holder. One is thereby obliged to take hold of the blade at the cutting corner, 30 which, apart from being difficult and painful, results in serious wound to the fingers. Owing to an insufficient grip, the blade falls out of the hand very easily, and thus becomes injured. Further, the two corner teeth, upon which the cutting corners of the 35 blade lie, are also rounded off, similar to the other teeth, and in consequence of this the cutting corners do not lie flat on the corner teeth, but stand out somewhat. The result of 40 this is that in the shaving of difficult parts of the face, such as the chin, etc., these corners cut into the skin. In other systems the blade is not adjustable, but is held fixed in the position for use, the cutting edge of the blade resting upon metal projections. It is quite 45 clear that in such an apparatus the fine edge of the blade is easily injured in use and thus is very soon spoiled. Thanks to the Pass casting system it is now possible to cast even 50 safety razors of a difficult form out of light metal in a practical manner, and to adapt thereto such appliances that the hollow ground blade lies rigidly and free of all vibration, the blade being independent of the 55 differences in exterior measurements and fitting exactly within the protecting comb. As 60 is seen in this invention, the well known projections are missing which are usually to be found at the side of the blade. The adjustment of the blade is now effected by means 65 of two long and wide guiding rails *c, d* which are so arranged that they are to be found under the blade in two exactly fitting guiding grooves *e, f* which are milled into the 70 underside of the amplified back of the 75 blade *a*. In this manner, and by means of the four sides of the two rails, four exact and large 80 lay-on surfaces are provided, instead of two small surfaces, such as are generally found in the ordinary safety razors, whilst at the same time an exact adjustment of the blade is assured, the movement of the blade in any direction being avoided. As the length of 85 the blade *a* lies free above the protecting comb *b*, and as it can be readily adjusted in its breadth by means of the long guiding rails *c, d*, the blade, independent of its size, fits exactly on the protecting comb, even when, 90 if new or if after having been reground after use, there are more or less unavoidable differences in the size of the blade. The interior sides of the grooves are not touched in the manufacture of the blade nor in the 95 grinding of same. Thus every blade fits exactly inside the guiding rails, and is also inserted into the protecting comb backwards, thus avoiding all contact of the cutting edge as well as all injury to the metal of the protecting comb. A sideways movement or an 100

irregular insertion of the blade when pushing same into the holder, or when regulating the position of the blade by means of the screws is thus rendered impossible, the cutting edge always lying exactly parallel with the teeth of the protecting comb. Further the hollow ground blade projects on both sides free of the protecting comb, with exception of the cutting edge which lies on the corner teeth of the protecting comb, so that it may easily be held in the fingers on both sides and placed within or extracted from the protecting comb without the fingers coming into contact with the cutting edge. The two corner teeth of the protecting comb are, contrary to the other teeth, arranged as flat guides without any rounding off, and hence the cutting edge of the blade lies flat thereon, in any position of the blade and even when adjusted. It is impossible for the cutting corners to cut into the skin when shaving.

The diagram indicates the description of the object of this invention.

Fig. 1 shows the insertion of the blade into the protecting comb.

Fig. 2 is a perspective view of the safety razor with the guiding rails.

Fig. 3 is a vertical longitudinal section.

Fig. 4 shows a back view of the blade with the guiding grooves.

What I claim is:

An improved safety razor comprising, in combination, a handle, a guard comb secured in the center to the handle, an adjustable hollow ground one edge hoe-typed safety razor blade with a wide back, projecting free with both ends above the guard comb, a spring clamp fixed to the guard comb for pressing the blade on to the guard comb, two regulating screws, the two corner teeth of the guard comb contrary to the other teeth, arranged as flat guides without any rounding off, the guard comb having on its upperside double guiding rails for adjusting the blade, the blade having double guiding grooves milled into the underside of the amplified back of the blade and adapted to fit onto the guiding rails of the guard comb providing four laying surfaces for the blades, for the purpose set forth in the specification.

PAUL MÜLLER.
